Primary Examiner—Ted Shooman*Assistant Examiner*—Nanda Bondade[57] **CLAIM**

The ornamental design for a stereo speaker mounting bracket, as shown and described.

DESCRIPTION

FIG. 1 is a front elevational view of a stereo speaker mounting bracket showing my new design; the broken line showing of the speaker is for illustrative purposes only and forms no part of the claimed design;

FIG. 2 is rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
